(57) **CLAIM**

The ornamental design for an antenna mount, as shown and described.

DESCRIPTION

FIG. 1 is a top-front-right perspective view of the antenna mount.

FIG. 2 is a bottom-rear-left perspective view of the antenna mount.

FIG. 3 is a top view of the antenna mount.

FIG. 4 is a bottom view of the antenna mount.

FIG. 5 is a front view of the antenna mount.

FIG. 6 is a rear view of the antenna mount.

FIG. 7 is a left side view of the antenna mount; and,

FIG. 8 is a right side view of the antenna mount.

In these drawings, the features shown in broken lines depict environmental subject matter only and form no part of the claimed design.
